UNITED STATES PATENT OFFICE.

GEORGE WILLIAM DOVER, OF CRANSTON, RHODE ISLAND, ASSIGNOR, BY MESNE ASSIGNMENTS, TO AMERICAN GUARANTEED TOOTH COMPANY, INCORPORATED, OF BOSTON, MASSACHUSETTS, A CORPORATION OF MASSACHUSETTS.

METHOD OF MAKING FALSE-TEETH BACKINGS FROM SHEET METAL.

1,313,528.

Specification of Letters Patent. Patented Aug. 19, 1919.

Application filed May 23, 1918. Serial No. 236,202.

To all whom it may concern:

Be it known that I, GEORGE WILLIAM DOVER, a citizen of the United States, residing at Cranston, in the county of Providence and State of Rhode Island, have invented a new and useful Improvement in Methods of Making False-Teeth Backings from Sheet Metal, of which the following is a specification.

10 In false teeth backings, formed from sheet metal, such as shown in United States Patents Nos. 377,248, and 1,159,309, the sheet metal is bent up so as to form a tube with wings at each side of the tube. This construction leaves a line of separation between the wings or plates and such backings as a whole are crude and weak in construction.

15 The object of my invention is to improve the method of making backings of sheet metal for porcelain teeth, said backing, which consists principally of a plate which lays against the inner face of the tooth and a central pin on the back of the plate which enters the tooth, the whole being solid in construction, like a casting, but stronger and more rigid than a casting, by the sheet metal being compressed in the various operations in forming up the backing.

20 Another object of my invention in improving the method of making false teeth backings of sheet metal is, to split the backing blank through its thickness, and to roll the split portions over and outward at each side, so as to form the plate of the backing out of the split portions of the blank.

25 My invention consists in the peculiar and novel method of making false teeth backings of sheet metal, as will be more fully set forth hereinafter and claimed.

30 Figure 1 is a side view of a sheet metal blank from which a false tooth backing is formed.

Fig. 2 is an edge view of the blank.

35 Fig. 3 is a longitudinal sectional view through the essential portion of a splitting die, showing a side view of the blank in the position to be split.

40 Fig. 4 is a transverse sectional view through the splitting die showing an end view of the blank in the position to be split.

Fig. 5 is a transverse sectional view similar to Fig. 4 with the die closed and the blank split.

Fig. 6 is a transverse sectional view through open dies that flatten out the split 55 and rolled over portions of the blank.

Fig. 7 is a sectional view similar to Fig. 6 showing the flattening dies closed and the split portions of the blank flattened out to form the transverse plate of the backing. 60

Figs. 8, 9, and 10 are side, end and back views respectively, showing the formation of the central round pin on the transverse plate.

Figs. 11, 12 and 13 are side, end and back views respectively, showing the bending of 65 the pin toward the plate, and

Figs. 14, 15 and 16 are side, end and back views respectively showing the bending of a portion of the plate parallel with the pin, thereby completing the final step in forming the tooth backing from sheet metal. 70

All of the figures are enlarged to more clearly show my invention.

In the drawings 1 indicates a blank struck from sheet metal by suitable dies and shaped 75 to have a flat body 2 from which extends at an angle a stem 3 as shown in Fig. 1. 4 a lower splitting die member in the form of a plate the same thickness as the blank to be split and having an opening 5 in its upper 80 edge shaped to receive the stem portion of the blank 1 as shown in Fig. 3. An upper splitting die member 6 carries a central splitting cutter 7 and separable bars 8. 8 at each side of the lower die member 4, the inner 85 top edges of the bars being on a line with the cutting edge of the splitting cutter 7 as shown in Fig. 4. The upper die member 6 also has above the bars 8, 8, a recess 9 with a flat bottom, at each side of the cutter. 90 Lower and upper flattening die members 10 and 11, the upper die member having the shallow flat bottomed recess 12, as shown in Figs. 6 and 7, are used to flatten out the split portions 13, 13 of the blank after it 95 comes from the splitting dies, to form a transverse plate 14 on the now partly completed backing.

My improved method of making false teeth backings from sheet metal consists in 100

striking out by suitable dies, a blank having a comparatively thin flat body 2 and an angular stem 3, as shown in Fig. 1, from sheet metal, placing the blank edgewise in a splitting die as shown in Fig. 3, said die having removable bars 8, 8 so as to hold the sides of the blank, at the point of splitting, as the blank is being split down, closing the splitting dies and splitting a predetermined portion 5 of the blank body 2 through its thickness, the split portions 13, 13 of the blank striking the flat bottom of the recesses 9, 9 in the upper die member 6 and rolling over on each side, as shown in Fig. 5 and the 10 inner top edge of the bars 8, 8 holding each side of the blank at the point where it is being split and simultaneously following down with the splitting cutter 7, placing the split blank in the flattening die members 10 and 11 and closing the die, thereby forming 15 a flat transverse plate 14 on the blank, as shown in Fig. 7, forming a round pin 15 out of the stem 3 which has a larger round base 16 connecting the pin to the plate 14, as shown in Figs. 8, 9 and 10, bending the 20 pin 15 and base 16 toward the plate 14 as shown in Figs. 11, 12 and 13, and then bending a portion 17 of the plate 14 parallel with the pin 15, as shown in Figs. 14, 15 and 16 25 thereby completing the tooth backing.

The principal operation in my improved method of making false teeth backings of sheet metal consists in splitting the sheet metal blank through its thickness and forcing the split portions over at each side, the split portions of the blank forming the 30 transverse plate for the pin.

By the use of my improved method of forming false teeth backings integral of sheet metal, an extremely strong and rigid 40 backing is formed, otherwise a backing of this kind in which the central pin on the back of the plate is formed integral with the plate, would have to be cast or the pin 45 soldered to the plate, either of which is not as strong, rigid or durable as the backing made by my improved method.

It will be seen that by the method above described, I produce in one piece, a plate 50 having opposite sides of substantial area, and a stem projecting from one side of the plate and integral therewith, the plate overhanging the stem in various directions. It will also be seen that the edge portion of the blank from which the stem 3 projects, 55 constitutes a neck-forming portion integral with the stem, and that the portion of the blank between said neck-forming portion and the opposite edge of the blank, constitutes a wing-forming portion adapted to be 60 split to form the oppositely projecting wings 13, integral with the neck. The splitting operation therefore results in the formation of a stemmed plate which includes the said

wings and a neck connecting the wings, and 65 overhangs the stem in various directions. A part of the neck-forming portion of the blank at one side of the stem 3, is offset or extended to provide material for an enlarged tenon portion or head 16, so that provision 70 is made for fashioning from a portion of the neck and from the stem 3, a tenon having an enlarged base portion 16, a reduced pin-like portion 15, and a web or neck portion 16^a (Figs. 11 and 12), said portions 75 constituting a tenon adapted to engage a correspondingly formed socket in a tooth body.

It will also be seen that by said method I produce a seamless stemmed plate entirely 80 free from seams or joints in the plate portion, in the stem portion, and in the web portion 16^a, each of said portions being solid and integral with the other portions. The term "solid" as applied to the stem and 85 web portions, is intended to convey the idea that the stem portion is not hollow or tubular, and has no joint or seam, and that the web portion does not comprise layers connected by a joint or seam.

The area of the flat sides of the wing-forming portion is greater than that of the sides of the solid stem-forming portion, so that in the completed article the plate overhangs the stem in various directions. By 95 this I mean that the plate overhangs the stem both crosswise and lengthwise, so that the base of the stem is within at least three of the edges of the plate, and preferably within four of said edges.

As shown by the drawings, the stem portion of the blank is inclined relatively to the wing-forming portion, so that in the completed article the pin or tenon is at an 100 inclination to the wings forming the plate, although a stemmed plate with the stem either perpendicular to or parallel with the plate may be produced with equal facility by the improved method.

Although my improved method is particularly adapted for making false teeth backings from sheet metal blanks, it is self-evident that by a slight change in the structure of the instrumentalities used, any other analogous thing that can be made of sheet 110 metal in this way, may be made by my improved method.

Having thus described my invention I claim as new:

1. The method of making false teeth backings from sheet metal consisting in striking out a blank of the required shape and thickness, from sheet metal, placing the blank edgewise in a splitting die and splitting a predetermined portion of the blank through its thickness, and simultaneously holding each side of the blank on a line with the splitting, as the blank is being split, plac-

- ing the split blank in flattening dies and flattening out the split portions of the blank to form a transverse plate on the blank, and forming the unsplit portion of the blank into 5 an angular central pin on the plate.
2. The method of making false teeth backings from sheet metal consisting in striking out a blank of the required shape and thickness, from sheet metal, placing the blank 10 edgewise in a splitting die and splitting a predetermined portion of the blank through its thickness, and simultaneously holding each side of the blank on a line with the splitting, as the blank is being split, placing the split blank in flattening dies and flattening out the split portions of the blank to form a transverse plate on the blank, and forming the unsplit portion of the blank into an angular central pin and connecting 15 web on the plate.
3. The method of making false teeth backings from sheet metal consisting in striking out a blank of the required shape and thickness, from sheet metal, placing the blank 20 edgewise in a splitting die and splitting a predetermined portion of the blank through its thickness, and simultaneously holding each side of the blank, on a line with the splitting, as the blank is being split, placing the split blank in flattening dies and flattening out the split portions of the blank to form a transverse plate on the blank, forming the unsplit portion of the blank into an angular 25 central pin on the plate and bending a portion 30 of the plate down parallel with the pin.
4. The method of making false teeth backings from sheet metal consisting in striking out a sheet metal blank having a comparatively thin flat body portion and a stem 35 at an angle to the body portion, placing the blank edgewise in a splitting die and simultaneously splitting the body of the blank through its thickness a predetermined distance, rolling the split portions over and 40 outward and simultaneously holding the sides of the blank at the line of splitting, as the blank is being split, flattening the split and rolled over portions of the blank into a flat plate in suitable flattening dies, forming the stem on the blank into a central 45 angular round pin on the back of the plate, bending the pin down toward the plate and bending a portion of the plate 50 parallel with the pin.
5. The improvement in the method of 55 making seamless stemmed plates, which consists in striking out from sheet metal a flat-sided blank having a wing-forming portion and a solid stem-forming portion, the 60 area of the sides of the wing-forming portion being greater than that of the sides of the stem-forming portion, and splitting and bending a part of said blank to form oppositely projecting wings integral with 65 each other, said wings overhanging the stem in various directions and being integral with the stem.
6. The improvement in the method of 70 making seamless stemmed plates which consists in striking out from sheet metal a flat-sided blank having a wing-forming portion and a solid stem-forming portion, inclined relatively to the wing-forming portion, the area of the sides of the wing-forming portion being greater than that of the sides 75 of the neck-forming portion, and splitting and bending a part of said blank to form oppositely projecting wings integral with each other, said wings overhanging the stem in various directions and being integral with the stem.
7. That improvement in the method of 80 making seamless stemmed plates which consists in striking out from sheet metal a flat-sided blank having a wing-forming portion, 85 a neck-forming portion, and a solid stem projecting from the neck-forming portion, the area of the sides of the wing-forming portion being greater than that of the sides of the neck-forming portion, and splitting 90 and bending a part of said blank to form oppositely projecting wings integral with each other, and a neck integral with and connecting the wings, said neck and wings 95 constituting a seamless plate which overhangs the stem in various directions, and is integral with the stem.
8. That improvement in the method of 100 making seamless tenoned backings for false teeth, which consists in striking out from sheet metal a flat-sided blank having a wing-forming portion, a neck-forming portion, and a solid stem projecting from the neck-forming portion and inclined relatively 105 thereto, the area of the sides of the wing-forming portion being greater than that of the sides of the neck-forming portion, splitting and bending a part of said blank to form oppositely projecting wings integral with each other, and a neck integral 110 with and connecting said wings, said neck and wings constituting a seamless plate which overhangs the stem in various directions, and is integral with the stem, forming said plate into an operative tooth backing, and forming said stem into an operative 115 solid and seamless tenon adapted to engage a socket in a tooth body.
9. That improvement in the method of 120 making seamless tenoned backings for false teeth, which consists in striking out from sheet metal a flat-sided blank having a wing-forming portion, a neck-forming portion, and a solid stem projecting from the neck-forming portion and inclined relatively 125 thereto, the area of the sides of the wing-forming portion being greater than that of the sides of the neck-

forming portion, a part of said neck-forming portion being offset at one side of the stem to provide material for a tenon head, splitting and bending a part of said blank to form oppositely projecting wings integral with each other, and a neck integral with and connecting said wings, said neck and wings constituting a seamless plate which overhangs the stem in various 10 directions and is integral with the stem, forming said plate into an operative tooth

backing, and forming said stem into an operative solid and seamless tenon which includes an enlarged base portion formed from the offset part of the neck-forming portion, and a reduced portion extending from said base portion, said tenon being adapted to engage a socket in a tooth body.

In testimony whereof, I have signed my name to this specification.

GEORGE WILLIAM DOVER.
